INCANDESCENT LAMP AND METHOD OF
MANUFACTURING THE SAMERoyal F. Strickland, Cleveland Heights, Ohio, as-
signor to General Electric Company, a corpo-
ration of New York

Application July 13, 1932, Serial No. 622,268

5 Claims. (Cl. 176—32)

My invention relates to bases for electric incandescent lamps and similar devices. More particularly my invention relates to such devices having bases which are comprised of insulating material molded directly thereon and are provided with metallic contact areas or terminals. Previous bases of this type usually incorporated relatively large terminal portions. In some cases this was due to the fact that the insulating material was rather brittle and required protection. In some cases metallic paste or paint coatings served for the terminals. My invention on the other hand contemplates terminals consisting of bodies of metal as distinct from such coatings.

One object of my invention is to provide an efficient base comprising parts of small size and low cost but of great durability as compared with previous bases. Other objects and advantages of my invention will appear from the drawings and the description which follows of a species thereof.

In the drawings Fig. 1 is a perspective view of a lamp embodying one species of my invention; Fig. 2 is a side elevation thereof with the base in place in a socket which is shown in section; Figs. 3 and 4 are side elevations partially in section of steps in the manufacture of said base; Fig. 5 is a perspective view of another species of my invention; Figs. 6, 8 and 10 are vertical sections through a portion of still other species of my invention; and Figs. 7, 9 and 11 are horizontal sections along lines 6—6, 8—8, and 10—10 respectively of the species shown in Figs. 6, 8 and 10.

In the specific embodiment of my invention shown in Fig. 1, the base comprises collar 10 and a substantially cylindrical portion 11 with oppositely disposed lateral ridges 12 extending longitudinally thereof. These portions are all formed from the molded material which is preferably composed principally of a synthetic resin, a hardening compound and a filler such as marble flour or the like. There are a number of such synthetic resins such as Bakelite. One such synthetic resin is commercially known as Durite which is a furfural or phenol formaldehyde product. This substance is preferred for its resistance to weathering and for its tendency to adhere to the glass as well as for its ability to mold easily at low pressures. This material is mixed with a hardening compound such as hexamethylene-tetramine and a filler which is non-compressible. An inorganic material such as alumina, magnesia, or silica will serve as a filler but marble flour is preferred. Along the outer edge of the ridges 12 are contact areas or terminals 13 connected to

filament 14 and, in the species shown in Fig. 1, are exposed portions of the leads 15 which are suitably bent preferably into loops. When the base is inserted into a socket 16, shown in Fig. 2, the contact areas are engaged by spring contact fingers 17 in longitudinal grooves 18 in the socket which guide the ridges 12 into position and the cylindrical portion 11 of the base is snugly engaged by a correspondingly shaped portion of the socket. Sockets of this type have sufficient grip upon the base to keep the lamp from being shaken out.

My method of molding the species shown in Fig. 1 consists, as shown in Figs. 3 and 4, in first bending the outer ends 19 of the leading-in wires 15 into the form shown and placing the lamp in holder 20. The holder is provided with a sponge rubber facing 21 so as to engage all portions of the irregular shaped bulb 22. The mold 23 is then brought down into contact with the bulb 20 in such a position that the leading-in wires will be properly placed in the mold whereupon the required amount of molding material is inserted into passage 24 and is pressed into all portions of the mold by plunger 25. The mold is now 25 heated, preferably to 165° C., until the base material has taken a permanent set whereupon the bulb holder 20 is removed and the completed based lamp removed from the mold. In order to prevent breakage of the bulbs, a molding pressure of from fifteen to one hundred and fifty pounds per square inch is used, which is sufficient for the molding material used. With this method of manufacture the base terminals are sections of the leading-in wires each of which 35 is bent into the looped form shown. This provides the two oppositely disposed terminals and serves also to resist displacement during the molding process.

Also included within the scope of my invention 40 are the other forms of my base shown in remaining Figs. 5 to 11 which comprise separate terminals united to the leads. The inserts 26, as shown in Fig. 5, preferably form the exterior surface of the longitudinal ridges in each case and 45 in the form shown in Figs. 6 and 7, are kept in contact with the leading-in wires both by the pressure of the molding material and by the springiness of the wires. Each wire is placed within the V of an insert before molding and is 50 forced further thereinto by the molding pressure. In the form shown in Figs. 8 and 9 the method of attaching the leading-in wires to the inserts differs in that said wires are soldered or 55 welded thereto before the base is molded. In

the form shown in Figs. 10 and 11, the leading-in wires are clamped to the insert by bending tongue 27 thereabout, as shown, before molding.

What I claim as new and desire to secure by Letters Patent of the United States is:

5. 1. An electrical device consisting of a glass enclosure having an electric energy translation element mounted therein and lead wires connected to said element and extending through 10 the said enclosure and a base consisting of an insulating substance molded on said enclosure and having embedded therein the ends of said lead wires, said base having at least one longitudinally extending protuberance at the side 15 thereof formed from said insulating material and having a portion of one of said lead wires exposed at the surface thereof to constitute a terminal.
2. An electrical device consisting of a glass enclosure having an electric energy translation element mounted therein and lead wires connected to said element and extending through the said enclosure and a base consisting of an insulating substance molded on said enclosure 20 and having embedded therein the ends of said lead wires, said base having at least one longitudinally extending protuberance at the side thereof formed from said insulating material and having a portion of a lead wire exposed and 25 extending along a portion of the surface thereof to constitute a terminal.
3. An electrical device consisting of a glass enclosure having an electric energy translation element mounted therein and lead wires connected 30 to said element and extending through the said enclosure and a cylindrical base consisting of

an insulating substance molded on said enclosure and having embedded therein the ends of said lead wires, said base having at least one longitudinally extending ridge at the side thereof formed from said insulating material and having 5 a terminal body exposed at the surface thereof of having electrical connection to one of said lead wires.

4. An electrical device consisting of a glass enclosure having an electric energy translation element mounted therein and lead wires connected to said element and extending through the said enclosure and a cylindrical base consisting of an insulating substance molded on said enclosure and having embedded therein the 10 ends of said lead wires, said base having at least one longitudinally extending ridge at the side thereof formed from said insulating material and having a portion of a lead wire exposed and 15 extending along a portion of the surface thereof to constitute a terminal.

5. An electrical device consisting of a glass enclosure having an electric energy translation element mounted therein and lead wires connected to said element and extending through 20 said enclosure, and a base consisting of an insulating substance molded on said enclosure and having embedded therein the ends of said lead wires, said base having at least one longitudinally extending protuberance at the side thereof, and the embedded end of a lead wire being 25 bent into an angular loop extending outward from the wall of said enclosure and having its midportion exposed at the surface of said protuberance to constitute a terminal. 30
